US0D1031014S

(12) **United States Design Patent** (10) **Patent No.:** **US D1,031,014 S**
(45) **Date of Patent:** **** Jun. 11, 2024**

(54) **RESPIRATION DEVICE**

(71) Applicant: **RAUMEDIC AG**, Münchberg (DE)

(72) Inventors: **Ricardo Ehrenpfordt**, Chemnitz (DE);
Tobias Festel, Sparneck (DE); **Thomas Ruhland**, Bayreuth (DE)

(73) Assignee: **RAUMEDIC AG**, Münchberg (DE)

(**) Term: **15 Years**

(21) Appl. No.: **29/730,070**

(22) Filed: **Apr. 1, 2020**

(30) **Foreign Application Priority Data**

Oct. 7, 2019 (EM) 006 986 717

(57) **CLAIM**

The ornamental design for respiration device, as shown and described.

DESCRIPTION

FIG. 1 is a front view of a respiration device, showing our new design;

FIG. 2 is a rear view thereof;

FIG. 3 is a top view thereof;

FIG. 4 is a bottom view thereof;

FIG. 5 is a lateral view (right side) thereof;

FIG. 6 is a lateral view (left side) thereof; and,

FIG. 7 is a perspective view thereof.

The broken line circles, and the area between the broken lines circles, illustrate portions of the article, and form no part of the claimed design.

1 Claim, 7 Drawing Sheets
